COIN SELECTOR AND SLUG REJECTOR

Harold A. Smith, Delavan, Wis., assignor to The
George W. Borg Corporation, Chicago, Ill., a
corporation of Delaware

Application January 15, 1945, Serial No. 572,849

26 Claims. (Cl. 194—97)

1

The present invention is a coin selector and slug rejector, adapted for use in connection with various types of coin operated machines such as vending machines, music machines, pay station telephones, etc., to prevent the fraudulent operation of such machines by means of slugs or counterfeit coins.

The invention may be considered as an improvement on the invention disclosed in U. S. Patent Re. 22,229, granted December 1, 1942, to Harold A. Smith, and employs a pair of dies each containing an impression of the coin to be selected, means for bringing about a fit between a deposited coin and one of the dies, and means including a suction device for causing the coin to adhere to the die temporarily, whereby the coin may be directed into a chute for the reception of genuine coins. A slug or a counterfeit coin is rejected by reason of the fact that it does not match the dies and will not adhere to either die, due to the excessive leakage of air.

The invention and various features thereof will be described more fully in the detailed specification which follows, and with reference to the accompanying drawings, in which—

Fig. 1 is a front view of a coin selector and slug rejector embodying the invention, with the front of the casing removed to expose the parts inside, certain of said parts being shown in section;

Fig. 2 is a top view of the same, with the top of the casing removed;

Fig. 3 is a section on the line 3—3, Fig. 2, and shows certain other parts, including a coin chute and part of the front wall of the casing of a vending machine or other machine in which the coin selector and slug rejector is incorporated;

Fig. 4 shows a gear with an integrally formed cam;

Fig. 5 shows the contour of the cam; and

Fig. 6 is a partial section through the coin chute on the line 6—6, Fig. 3.

Referring to the drawings, the mechanism is enclosed in a metallic casing comprising the front 10, back 11, bottom 12, sides 13 and 14, and top 15. The back, bottom and sides of the casing are preferably formed integrally from a single piece of material, which is bent to the proper shape in a suitable fixture. The front and top of the casing are also formed in one piece. The sides and bottom of the casing are provided with ears such as 16, 17 and 18, Fig. 1, to which the front of the casing may be secured by means of screws as shown in Fig. 2.

Near the top of the casing are two supporting blocks 20 and 21, the shape of which can be seen

2

from Figs. 1 and 2. The block 20 is secured to the side wall 13 of the casing by screws 24 and 25, while block 21 is secured to the side wall 14 of the casing by screws 26 and 27. These blocks rigidly support the two rods 22 and 23 which extend across the casing between the blocks.

The reference character 31 indicates a yoke which is slidably mounted on the rods 22 and 23 and is urged to the left by the two springs 32 and 33. These springs surround the rods 22 and 23, respectively, and are compressed between the yoke 31 and the block 21. The yoke 31 is additionally supported by means of two pins 34 and 35 which are fixed in the yoke and are slidable in the block 21.

There is a corresponding yoke 30 on the left hand side which is slidable on the rods 22 and 23 like yoke 31 and is urged to the right by the two springs 36 and 37. The pins 38 and 39 are fixed 10 in yoke 30 and are slidable in the block 20. The position of the yokes 30 and 31 is controlled by two cams, as will be described presently.

The reference characters 40 and 41 indicate two coin gripping cylinders which are supported 25 on the yokes 30 and 31, respectively. The cylinder 40 has an internal bevel 42 at the right hand end, the smaller diameter of which is the same as or slightly less than the diameter of the coin to be selected. At its left hand end the cylinder 40 30 has an annular recess in which the flexible disc 43 is secured by staking. The disc 43 is secured to the yoke 30 by means of a headed sleeve 41, which has a press fit in the yoke and is additionally secured by staking. A ring 46 is interposed 35 between the yoke and the disc, which is clamped between the ring and the head of the sleeve.

The cylinder 41 is supported on the yoke 31 in the same way that cylinder 40 is supported 40 on yoke 30. It will be seen that the discs such as 43 provide flexible connections between the cylinders and the yokes, whereby the cylinders are adapted to yield or tilt slightly to adjust themselves to a coin, which may not be of uniform thickness around the rim. The operation of the cylinders in gripping and holding a deposited coin will be explained presently.

The reference character 44 indicates a die which is supported on the tubular shaft 49. The 50 shaft has a bearing in the sleeve 47 and another bearing in the air seal washer 51 which is preferably made of Bakelite. A pinion 52 is secured to shaft 49 by means of a set screw. The yoke 30 has a rectangular opening, seen clearly in Fig. 2, 55 to provide room for the pinion 52. This opening

is larger than the pinion 52, and thus the shaft 49 is permitted to have a limited axial movement in its bearings in addition to its rotary movement. The shaft is urged toward the right by a spring 50 which is compressed between the washer 51 and the pinion 52, so that the pinion normally bears against the right hand side of the opening in yoke 30.

The die 44 is supported on the shaft 49 by means of a disc 45, which is staked on the shaft, and a rubber ring 43 which is cemented or molded to the back of the die. The ring 43 has an internal groove and is resilient enough so that it can be slipped on or off the disc.

The die 44 is preferably made of glass and has on its face an impression of the coin to be selected, as shown in Fig. 3. There are a plurality of small openings connecting the face of the die with the back thereof and forming air passages through the die. These openings are preferably two in number and are located in elevated areas on the face of the die. One opening is indicated at 53 in Fig. 3. Another opening, which is almost diametrically opposite opening 53, is indicated by dotted lines in Fig. 1. Each opening is connected to the nearest adjacent depressed area in the face of the die by a bleeder channel such as 55.

The cylinder 41 is mounted on yoke 31 in the same way that cylinder 40 is mounted on yoke 30. Other parts on the right hand side correspond to those on the left hand side which have just been described. The die 54 is identical with die 44 and is supported on the tubular shaft 56 which carries the pinion 57. The shaft 56 has bearings in the yoke 31 and in the block 21 and has a limited axial movement relative to the yoke. Spring 58 urges the shaft assembly to the left and normally holds the pinion 57 against the left side of the opening in the yoke 31.

The reference character 60 indicates the gear mounting block which extends between the front and rear walls of the casing and is firmly secured to the rear wall 11 by means of four screws such as 61 and 62. The block 60 is substantially square in cross section and has plane surfaces on all four sides except for a semi-circular recess 63 on the upper surface which is cut out to provide room for the cylinders 40 and 41. The block also has a number of slots which extend downward from its upper surface.

The slot 64 is the slug return slot or chute, and can be seen in Figs. 1 and 2, being partly shown also in Fig. 3, where the bottom of the slot is defined by the solid line 65 and the dotted continuations of this line. It will be seen that this return slot 64 is located directly beneath the space between the two dies 44 and 54 and that it slopes downward toward the front wall 10 of the casing. There is of course a slot in the front wall of the casing which is aligned with the slot 64 in the block.

There are two coin collect slots indicated at 66 and 67, Fig. 2, which are symmetrically located on opposite sides of the slug return slot 64. One of these coin collect slots, slot 66, can be seen in Fig. 1. The dotted line 68 in Fig. 3 defines the bottoms of the two coin collect slots and shows that they slope downward toward the rear wall 11 of the casing. There are two slots in the rear wall which are in alignment with the slots 66 and 67, respectively.

In addition to the slug return and coin collect slots described, the block 60 has a narrow slot 69, Fig. 2, which extends from the slug return slot 75

64 to the rear end of the block. The depth of the slot 69 is indicated by the dotted line 70, Fig. 3. It is provided in order to permit necessary movement of the coin actuated switch lever 115, as will be explained shortly.

The gear 71 is rotatably supported on the block 60 by means of a headed shoulder pin or stud 72, the shank portion of which has a drive fit in a hole drilled transversely through the block. The opposite gear 73 is similarly mounted on the block 60 by means of a stud 74. The gears 71 and 73 are in mesh with the pinions 52 and 57, respectively, and are driven in opposite directions by the gear 75, which is mounted on the lower side of block 60 by means of the stud 76.

The gear is driven by the pinion 78 on shaft 79, which in turn is driven by the motor 77 through the medium of suitable speed reducing gears. The motor is mounted on the rear wall 11 of the casing as shown. The motor unit including the speed reducing gears is of known construction and need not be described in detail. It may be mentioned, however, that the speed reduction should be such that the gears 71 and 73 rotate at a speed of from about 45 R. P. M. to 60 R. P. M.

The gears 71 and 73 are provided with integrally formed cams 80 and 81, respectively, which control the sliding movement of the yokes 30 and 31 on the rods 22 and 23. Gear 73 and cam 81 are shown in Fig. 4. The contour of the cam is shown in Fig. 5, from which it will be seen that the working face includes a long gradually rising portion 82, a flat portion 82', a short rapidly descending portion 83 terminating in a shallow depression 85, and a short rapidly descending portion 84. The gear 71 and cam 80 are identical with gear 73 and cam 81. The two cams engage rollers 86 and 87, respectively, which are mounted on the yokes 30 and 31 as shown. The gears are so assembled with the gear 75 that corresponding points on the cams engage the rollers simultaneously, in order to secure synchronous operation of the yokes 30 and 31.

The cams 80 and 81 also operate two suction devices each of which is in the form of a bellows. The left hand bellows 88 is shown in section and comprises two metal plates 90 and 91 which are hinged together at the bottom as indicated at 93 and which are connected at the edges all around by an accordion pleated fabric such as rubber, which is impervious to air. The plate 90 is secured to the side wall 13 of the casing by means of two screws such as 28 at the top and a screw 94 at the bottom. The plate 91 has a metal strap 95 outside, preferably secured to the plate by spot welding. The upper end portion 96 of strap 95 is bent away from the plate 91 as shown and engages the head of stud 72, which acts as a stop. Another part 97 struck out from the body of the strap 95 is also bent away from plate 91 and forms a support for the roller 99. Another part 98 is struck out from the body of strap 95 and is bent to form a hook for the spring 100. The plate 91 has an opening at 101, which is closed by the rubber flap 102. This flap is effective to permit the egress but not the entrance of air and acts as a valve.

The bellows 89 is in all respects the same as bellows 88 and accordingly need not be described in detail.

The spring 100 is tensioned between the hook 98 on bellows 88 and a corresponding hook 103 on bellows 89 and normally maintains both bellows in expanded condition. The bellows 88 is compressed by the cam 80 acting on roller 99,

while the bellows 89 is compressed by the cam 81 acting on the roller 104.

The plate 105 is secured to the wall 13 of the casing by means of screws 24 and 25, Fig. 2, and two screws such as 28, Fig. 1, and has a raised bead 106 which forms a channel communicating at its lower end with the interior of the bellows 88 by way of aligned openings in the wall 13 and plate 90. A gasket 107 is interposed between the plate 105 and wall 13. At its upper end the channel formed by bead 106 communicates with the bore 108 in block 20 and the bore 109 which is in communication with the interior of the tubular shaft 49. Bore 109 is of smaller diameter than bore 108. The valve member 110 is formed from a disc of Bakelite of the same diameter as the bore 108. The spring 111 is compressed between a perforated concave washer which rests against the gasket 107 and the valve member 110 and holds the latter against the shoulder which is formed at the junction of bores 108 and 109. The valve member 110 has a number of small holes therein located on a circle of slightly smaller diameter than bore 109 so that it does not shut off communication between bores 108 and 109. The function of the valve member 110 is to close the end of the tubular shaft 49. When the shaft 49 and associated parts are moved to the left by the yoke 30, the shaft engages the valve member 110 near the end of the movement and the shaft is effectively sealed. The reason for this operation will be explained later on.

The bellows 89 is connected with the tubular shaft 56 by air passages which are the same as those described for bellows 88, and a valve similar to valve 110 is provided in block 21 to seal the shaft 56.

When a coin is deposited it is supported in selecting position by means of a coin locator 112 and a switch lever 115, both of which extend into the space between the coin gripping cylinders 40 and 41. The coin locator 112 is made from a sheet metal stamping, bent to the form shown in Fig. 2, and is pivoted on the rod 23. A spring 113 is tensioned between a hook on slide 114 and the coin locator 112 and maintains the forwardly extending part of the coin locator in engagement with the slide, as shown in Fig. 1. In this position the rearwardly extending rounded end or nose of the coin locator is opposite the center of the die 44, as seen in Fig. 3, and is separated from the axis of the die by a distance equal to the radius of the coin to be selected.

The switch lever 115 is also made from a sheet metal stamping, and is formed as shown in Fig. 2. The switch lever is pivoted on the rod 22 and its forwardly extending rounded end, shown dotted in Fig. 3, projects somewhat farther into the space between the gripping cylinders 40 and 41 than the coin locator 112. The upwardly extending part of the switch lever 115 has a projection which bears against a bushing on the end of contact spring 118.

The contact springs 118 and 119 are mounted on the rear wall 11 of the casing by means of screws, spacers and insulators, as shown in Figs. 1 and 2.

The socalled cam lever is made from a sheet metal stamping, like the coin locator and switch lever, but has a somewhat more complicated form. It comprises two ears 120 and 121 by means of which it is pivoted on the rod 22, an upwardly extending part 122 which connects the ears 120 and 121, a part 123 which extends downward for a short distance from ear 121 and then

horizontally to the right as seen in Fig. 2, and an arm 125 which extends downwardly and to the left as seen in Fig. 3. The upwardly extending part 122 of the cam lever lies between two pins 116 and 117 fixed to the switch lever 115 and has a tapped hole in which the adjusting screw 124 is threaded. A spring 126 is mounted on the rear wall of the casing in the spring assembly which includes the contact springs 118 and 119 and has its end bearing on the part 122 of the cam lever, as shown clearly in Fig. 2. The spring 126 is tensioned to the rear and maintains the end of the adjusting screw 124 in engagement with the rear wall 11 of the casing.

The contact spring 118 is also tensioned to the rear and maintains the pin 117 on switch lever 115 in engagement with part 122 of the cam lever, thus determining the normal position of the switch lever. When a coin is deposited the periphery of the coin contacts the rounded end of the coin locator 112 and the rounded end of the switch lever 115 and the latter is rotated in a counter-clockwise direction until the end of the switch lever is substantially the same distance radially from the axis of the dies as the end of the coin locator, at which time the rotation of the switch lever is stopped by the engagement of pin 116 with the part 122 of the cam lever. In rotating as described the switch lever moves the contact spring 118 into engagement with contact spring 119, spring 118 being adjusted with such a light tension as to permit this operation. The spring 126, however, which bears against the part 122 of the cam lever, is too stiff to allow the cam lever to be operated by the coin.

It will be seen now that the operated position of the switch lever can be adjusted by means of the adjusting screw 124 so that a deposited coin will be very accurately located with respect to the dies and the gripping cylinders, with the center of the coin in substantial alignment with the axis of the dies. The coin is held suspended in this position, that is, it cannot fall through, because the end of the switch lever is angularly spaced from the end of the coin locator by only about 145 degrees and the distance between them is less than the diameter of the coin.

The contact springs 118 and 119 constitute a switch for controlling the motor 77 and are connected in series with one of the power supply conductors extending to the motor. The motor terminals are indicated at 160 and 161. The wiring is not shown but will be readily understood.

The hub 130 of gear 73 is utilized as a cam for operating the cam lever and to this end is provided with a notch 131 into which the arm 125 normally extends. When the motor is started by the closure of switch 118-119 responsive to the deposit of a coin the cam 130 rotates in a clockwise direction as seen in Fig. 3 and the left hand end of the notch 131 engages the arm 125, thereby rotating the cam lever in a counter-clockwise direction until the end of the arm rides up on the cam outside the notch. When the cam lever is rotated as described the part 122 engages pin 117 and rotates the switch lever 115 far enough so that the end thereof clears the slug return slot. The slot 69, hereinbefore referred to, is provided to enable the switch lever to make this movement. The parts remain in this position, with switch 118-119 closed, until the cam 130 has rotated far enough for the arm 125 to drop into the notch 131 again, whereupon the cam lever and the switch lever return to the positions in which they are shown in Fig. 3.

The slide 114, previously referred to, is shown in Figs. 1, 2 and 3. Only one half of the slide appears in Fig. 1, but it will be understood that the other half is symmetrical with the half that is shown. The general shape of the slide is that of an inverted U. The two legs 132 and 133 have an angular cross-section, as shown clearly in Fig. 2, where the block 60 is shown partly in section to expose the leg 133, also shown in section. The slide is supported on the block 60, which is provided with vertical grooves in which the legs 132 and 133 are received. The spring 134 is tensioned between the top of block 60 and a projection 136 formed at the lower end of leg 133 and with a corresponding spring associated with leg 132 maintains the slide in its uppermost position, in which the shoulder 135 and a corresponding shoulder at the left hand side of the slide engage the top 15 of the casing. One purpose for which the slide 114 is provided is to enable the yokes 30 and 31 to be operated, or moved in opposite directions, by hand, and to this end the slide has diverging sides above the junction of the two legs, forming cams 137 and 138 which engage the yokes 30 and 31 when the slide is moved downward. The depression of the slide also rotates the coin locator 112 and moves the rounded nose thereof out of the space between the gripping cylinders 40 and 41.

It may be assumed that the coin selector and slug rejector is incorporated in a vending machine which includes a casing of which a part of the front wall is indicated at 140 in Fig. 3. The coin selector and slug rejector may be fastened to the wall 140 by means of two screws such as 142 and two more screws below. The wall 140 has a slot in alignment with the slug return slot 64 and is provided with a cup 141 in which returned slugs or defective coins are deposited.

The coin chute 143 is attached to the top 15 of the casing as shown and projects through the wall 140. Two springs 144 and 145 are attached to the sides of the coin chute and, as shown in Fig. 6, have curved portions which project through openings in the coin chute. The springs are accordingly adapted to be engaged by a coin passing down the chute but are very flexible or limber and consequently will not stop a proper coin. The purpose of these springs will be explained presently.

The lever 146 is pivoted on a bracket 147 attached to the top 15 and extends to the left past the coin chute 143. Beyond the coin chute the lever rests in a slot at the end of slide 114 and passes through a slot in the wall 140. An operating knob 148 is provided at the end of the lever. Where it passes the coin chute 143 the lever 146 is bifurcated and has two curved arms such as 149 which lie close to the sides of the coin chute. These arms have wedge shaped ends such as 150 which are adapted when the lever is depressed to enter between the springs 144 and 145 and the adjacent sides of the coin chute to separate the springs.

The depression of lever 146 is also effective to operate the slide 114 and a small lever 151 which extends through the top 15 of the casing. When lever 151 is operated the end of the lever engages spring 119 and moves it out of the range of spring 118. The end of lever 151 may be provided with an insulating sleeve (not shown) to prevent grounding of the motor circuit on the casing.

A coin chute 152, partly shown in Figs. 2 and 3, is secured to the back wall 11 of the casing and is adapted to receive coins from the collect

slots 66 and 67 and direct them to the coin actuated mechanism of the vending machine.

The operation of the coin selector and slug rejector will now be explained. For this purpose it will be assumed first that a good coin is deposited in the coin chute 143.

When the coin is deposited it rolls down the chute, passes between the springs 144 and 145, which do not retard its descent appreciably, and 10 is delivered to the space between the coin gripping cylinders 40 and 41, where it comes to rest with its periphery in engagement with the coin locator 112 and the switch lever 115. The switch lever is operated by the coin and rotates on rod 22 15 until pin 116 engages the part 122 of the cam lever. This movement of the switch lever enables the coin to align itself with the gripping cylinders and also closes the switch 118-119.

The closure of the switch starts the motor 71, 20 which begins to run and drives the shaft 79, which drives the gear 75 by means of the pinion 78. The gear 75 drives the gears 71 and 73 and these gears in turn drive the pinions 52 and 57 which are fixed on the tubular die shafts 49 and 25 56. The rotation of the dies is thus started and continues until the coin is selected and the motor stops.

The direction of rotation of the motor is such that gear 71 rotates in a clockwise direction as 30 seen from the left in Fig. 1, while gear 73 rotates in a clockwise direction as seen from the right. The integrally formed cams 80 and 81 rotate in the same directions as their associated gears and accordingly the rollers 86 and 87 leave the depressions such as 85, Fig. 5, in the cams and ride down on the sharply sloping portions such as 84. The yokes are thus released by the cams and yoke 30 is moved to the right by springs 36, 37 and 50, while yoke 31 is 40 moved to the left by springs 32, 33 and 58. The shafts 49 and 56 and the dies 44 and 54 supported thereon move with the yokes.

The dies 44 and 54 engage the coin first and are 45 pressed against the opposite sides of the coin by the springs 50 and 58. The movement of the yokes and the gripping cylinders 40 and 41 continues independent of the dies for a short distance or until the beveled edges of the gripping cylinders engage the rim of the coin. The gripping 50 cylinders are now pressed against the coin by springs 32, 33, 36 and 37, while the dies are independently pressed against the coin by springs 50 and 58.

An instant after the coin has been seized by the 55 gripping cylinders 40 and 41 the cam 130 engages arm 125 and rotates the cam lever on the rod 22. This operation rotates the switch lever to clear the slug return slot and holds the switch 118-119 closed independent of the deposited coin.

At this time also the cams 80 and 81 engage the rollers 99 and 104 and start to compress bellows 88 and bellows 89. In this operation the air is expelled from bellows 88 by way of valve 102 and from bellows 89 by way of a similar valve.

60 While the bellows are being compressed the dies are being rotated for the purpose of enabling the coin to enter one of the dies. This testing period is divided into two stages, a first stage extending up to the time when the coin enters one of the dies and a second stage starting at this time and 70 extending up to the time when the dies are separated. During the first stage the coin is held against rotation by the gripping cylinders. The springs such as 32 are rather weak and press the gripping cylinders against the coin with a moder-

ate pressure, which is sufficient to hold the coin against rotation nevertheless because the dies rotate in opposite directions and the rotative torque applied to the coin by one die is substantially balanced out by the torque applied by the other die. During the second stage the torque applied to the coin by the die which it has entered is much the greater and the coin rotates with this die against the friction imposed by the gripping cylinders and the torque impressed by the other die. The springs 50 and 58 should apply sufficient pressure to the dies to prevent a coin which has entered a die from leaving it but the pressure should not be so excessive as to cause unnecessary wear on the dies. The adjustment of the springs is not critical.

The testing period covers the time during which the gradually sloping portions such as 82 of the cams 80 and 81 are in engagement with the rollers 99 and 104 and is long enough so that the dies each make somewhat more than one complete rotation. This insures that the coin will have a chance to enter one of the dies.

At the end of the testing period, when the bellows are fully compressed, the sharply sloping portions such as 83 and 84 of the cams pass the rollers 99 and 104 with the result that the bellows are released and are quickly expanded by the spring 100. A partial vacuum is established in each bellows, therefore, which tends to produce a flow of air through the associated die. As regards the die not entered by the coin, the holes in the die are not closed to any great extent, the flow of air through the die is substantially unobstructed, and the partial vacuum established by the expansion of the bellows is very quickly satisfied. As regards the other die, which has been entered by the coin, the openings in the die are so effectively sealed by the coin that the air flow through the die is very small and the vacuum in the air passage behind the die in the associated bellows is only very gradually reduced.

The parts such as 82 of the cams 80 and 81 now come into engagement with the rollers 86 and 87 and move the yokes apart, yoke 30 moving to the left and yoke 31 moving to the right. The yokes move independent of the dies for a short distance, thus disengaging the gripping cylinders from the coin. Shortly after this has occurred the yokes engage the pinions 52 and 57, whereupon the dies separate and move to the left and right, respectively, along with the yokes.

Assuming now that the coin has entered the die 44, the openings such as 53 in the die will be substantially sealed by the coin, there will be a partial vacuum behind the die and the air pressure on the outside of the coin will cause it to adhere to the die. As the die moves to the left, therefore, the coin is carried along and is positioned directly above the coin collect slot 66 as the movement is completed. Just before this occurs the end of the tubular shaft 49 engages the valve member 110 which seals the shaft and stops the flow of air from the back of the die to the interior of the bellows. The space behind the die and in the hollow shaft 49 is very small as compared to the space inside the bellows and the partial vacuum behind the die is almost instantly relieved by the leakage of air around the coin and through the holes in the die, whereupon the coin drops into the collect slot 66 and passes down the chute 152 to the coin operated mechanism of the vending machine. It will be observed from Fig. 5 that the sloping portion 82 of the cam terminates in a short flat portion 82'. These flat portions of

the cams hold the dies stationary in their extreme left and right hand positions, respectively, for an interval which is long enough for the selected coin to be released as described.

As the rotation of the cams continues the sharply descending portions such as 83 come into engagement with the rollers 86 and 87, thereby permitting the yokes 30 and 31 to move toward each other under the power supplied by the springs 32, 58, etc. As the yokes start this movement the arm 125 of the cam lever drops into the notch 131 on cam 130 and the cam lever and switch lever 115 are restored, opening the switch 118-119 to stop the motor 71. The yokes continue to move, however, due partly to the inertia of the motor armature and partly to power supplied by the springs, until the depressions such as 85 in the cams, reach the rollers 86 and 87, whereupon the apparatus comes to rest. The parts are now in their normal position, the position in which they are shown in the drawings, and the coin selector and slug rejector is ready for the deposit of another coin.

It will be understood that if the coin had been deposited the other way around it would have been selected by the die 54 and would have been dropped into the coin collect slot 67.

If a slug is deposited, the coin selector and slug rejector goes through the same cycle of operations as when a good coin is deposited, assuming, of course, that the slug is of substantially the same size and weight as the coin, and it will not be necessary to repeat the explanation. The only difference is in the result, the slug being rejected and returned. This is due to the fact that the slug cannot enter either die and when the dies are separated it drops directly down into the slug return slot which directs it into the cup 141.

The opening in the coin chute 143 should conform quite closely to the size of the coin to be selected so that a slug which is larger than the coin cannot be inserted. A slug which is substantially smaller than a coin will not be retained in selecting position by the switch lever 115 and the coin locator 112 but will fall through into the slug return slot immediately. There may be some slugs, however, which will be retained in selecting position when deposited but will not operate the machine. A slug made of aluminum, for example, may conform closely to a coin in size but may be too light to operate the switch trigger 115 to close the switch and start the motor.

In order to remove a slug of the last mentioned type the lever 146 is operated by means of knob 148. The operation of the lever, it is pulled downward, depresses the slide 114, the cams 137 and 138 of which engage the yokes 30 and 31, respectively, and move them in opposite directions. At the same time the slide 114 rotates the coin locator 112 on rod 23, thus clearing the path to the slug return slot 64 and allowing the slug to be returned.

It is possible also for a very thin slug or badly worn coin to become wedged between one of the dies and the switch lever or the coin locator. Such a slug or coin may be dislodged and returned by operating the lever 146 as described, which moves the dies farther apart and allows the slug or coin to fall.

The coin selector and slug rejector will unerringly accept and collect all genuine coins of the denomination for which it is designed, even if such coins are worn to a considerable extent. A very badly worn coin is returned. The machine will just as surely reject and return all slugs, how-

ever closely they simulate a coin in size and weight. In this connection it may be mentioned that the location of the openings such as 53 on elevated areas in the face of the die and the provision of the bleeder channels such as 55 are of considerable importance as this arrangement makes it impossible for a flat smooth slug to seal one of the openings and be selected.

The machine will also reject most counterfeit coins. A counterfeit coin may so closely resemble the genuine coin that it defies detection by ordinary inspection, yet if it differs in size even very slightly or if the design varies in any detail, it will not enter the die and will be rejected.

In the case of a coin selector and slug rejector intended for the selection of coins of a denomination of which there are two designs in circulation, the dies have a composite impression of both designs. For example, a machine built for use with U. S. coins of the five cent denomination uses dies having a composite impression of one side of a "buffalo" nickel and one side of the "Jefferson" nickel and will select coins of both designs equally well.

An important consideration for the successful operation of the coin selector and slug rejector is that the dies be kept clean and free of all sticky substances which might cause a good coin to fail to enter a die or a coin or slug to adhere to a die independent of air pressure. Coins in general circulation are clean, or at least are free from sticky materials, and cannot cause any trouble. However, it is known, that a coin will occasionally become contaminated with some sticky substance such as chewing gum, for example, either by accident or with the intention on the part of the owner of the coin of defrauding the vending machine. Such purpose cannot be effected, of course, but in the operation of the machine responsive to the deposit of a coin or slug so contaminated some of the sticky substance might adhere to the dies or to one of them, rendering the machine inoperative and necessitating a service trip to clean the dies.

The attachment on the coin chute 143 comprising the springs 144 and 145 is designed to eliminate trouble from the source above referred to. When a clean coin or slug is deposited it slides down the chute without being perceptibly delayed by the springs 144 and 145, but if a coin or slug having some sticky substance such as gum adhering thereto is deposited the movement of such coin or slug is arrested by the springs and it is held up in the coin chute.

The suspended coin or slug may be retrieved by operation of the lever 146 which spreads the springs 144 and 145 apart and allows it to fall down the coin chute. The operation of the lever also operates the slide 114 as previously described thereby spreading the dies apart so that the descending coin or slug will not contact either die as it passes through the machine to the return cup 141. If the sticky coin or slug is left in the coin chute the next person who deposits a coin will be advised that the chute is obstructed by the fact that the deposited coin does not go down and will operate the lever 146 to clear the obstruction, thereby returning all coins or slugs which at that time may be in the coin chute.

It is to be noted that the operation of the lever 146 does not spread the dies and gripping cylinders far enough to expose the coin collect slots 66 and 67. All coins or slugs dislodged by operation of the lever therefore pass into the slug return slot.

The invention having been described, that which is believed to be new and for which the protection of Letters Patent is desired will be pointed out in the appended claims:

5. I claim:

1. In a coin selector and slug rejector, means for supporting a coin in selecting position, means including a die for selecting said coin, means for rotating said die in contact with said coin, and 10 means for holding said coin against rotation until it enters said die.

15 2. In a coin selector and slug rejector, means for selecting a coin including a pair of dies having face configurations adapted to fit one side of said coin, said dies being of smaller diameter than said coin, means for bringing said dies in contact with the opposite sides of said coin, respectively, means for rotating said dies, and means for frictionally gripping said coin outside the margin of 20 said dies with a force sufficient to prevent rotation of the coin until it enters one of said dies.

25 3. In a coin selector and slug rejector, means for selecting a coin including two dies having face configurations adapted to fit one side of said coin, 25 two gripping members for engaging the rim of said coin to hold the same, resilient means for pressing said dies against the opposite sides of a deposited coin, independent resilient means for operating said gripping members, and means for 30 rotating said dies in opposite directions.

35 4. In a coin selector and slug rejector, two supports slidably mounted for movement toward and away from each other, two dies slidably mounted on said supports, resilient means for moving said supports and dies to cause the dies to engage a deposited coin on opposite sides thereof, two gripping members mounted on said supports, respectively, and additional resilient means for continuing the movement of said supports independent of 40 said dies to cause said gripping members to engage and hold said coin.

45 5. In a coin selector and slug rejector, means for supporting a deposited coin in selecting position, a perforated die having an impression of said coin, means for rotating said die against said coin to enable said coin to enter the die, a bellows, means for compressing said bellows while said die is rotating, means for releasing said bellows after the coin has entered the die, a spring for quickly expanding said bellows, and means including an air passage connecting said bellows with the back of the said die, whereby air is drawn through the die to cause said coin to adhere thereto.

55 6. In a coin selector and slug rejector, a die having one or more air passages extending from the face of the die to the back thereof, said die being made of glass, a hollow shaft, means for resiliently supporting said die on said shaft, said means forming a closed air passage connecting the air passage or passages in the die with the interior of the shaft, and means for applying suction to said shaft to draw air through said die, whereby a coin engaged by the die may be caused to adhere thereto.

65 7. In a coin selector and slug rejector, a die having an impression of a coin on its face, a hole extending through the die from an elevated area of said impression, a channel in the face of the die connecting said hole with a depressed area of said impression, and means for applying suction to the back of the die to draw air through said hole.

70 8. In a coin selector and slug rejector, a die 75 having one or more air passages extending from

the face of the die to the back thereof, a rubber ring secured to the back of said die outside said air passages, said ring having an internal groove, a flexible disc the periphery of which is located in said groove, a tubular shaft on which said disc is supported, the end of said shaft projecting through said disc, and means for exhausting air through said shaft and die.

9. In a coin selector and slug rejector, means for supporting a deposited coin in selecting position, a switch operated by the coin in said position, a motor started by said switch, a rotatable die axially movable on its rotation axis to engage said coin, and means operated by said motor for controlling the axial movement of said die and for rotating said die to establish a fit with the coin.

10. In a coin selector and slug rejector, means for supporting a coin in selecting position, a switch operated by said coin in selecting position, a motor started by said switch, means for selecting said coin including a rotatable reciprocating die and a suction device for causing the coin to adhere to the die, and means for transmitting power from said motor to operate said die and suction device.

11. In a coin selector and slug rejector, a die containing an impression of a coin, means for manipulating said die to establish a fit with a deposited coin and to select the same, a motor supplying power to operate said means, means responsive to the deposit of said coin for starting said motor, and means actuated by the motor for causing the motor to run independent of said coin until the same is selected.

12. In a coin selector and slug rejector, a slug return chute, means including a switch actuating member for holding a deposited coin or slug suspended above said chute, a switch operated by said member, a motor controlled by said switch, means operated by said motor for holding and testing said coin or slug, and means operated by said motor for maintaining said switch closed during the testing operation and for moving said member to clear the path to said return chute so that when a slug is tested it may be rejected.

13. In a coin selector and slug rejector, a pair of dies adapted to engage the opposite sides, respectively, of a deposited coin, two axially movable and rotatable shafts on which said dies are supported, two pinions fixed on said shafts, respectively, two gears meshing with said pinions, respectively, means for driving said gears to rotate said shafts and the said dies supported thereon, and means including cams rotating with said gears for controlling the axial movement of said shafts while the same are rotating.

14. In a coin selector and slug rejector, a rotatable die, means including a gear for rotating said die, a spring for moving the rotating die against a deposited coin, and a cam rotating with said gear and controlling the movement of said die under the power supplied by said spring.

15. In a coin selector and slug rejector, a rotatable die, means supporting said die for reciprocating motion along its rotation axis to select a deposited coin, a spring supplying power for movement of said die in one direction, means including a gear for rotating said die, and a cam rotating with said gear for controlling the movement of said die in the direction in which it is moved by said spring and for moving said die in the opposite direction.

16. In a coin selector and slug rejector, two dies each containing an impression of a coin

to be selected, two shafts supporting said dies, respectively, pinions on said shafts, two gears meshing with said pinions, a third gear meshing with said first mentioned gears to drive the same in opposite directions, and means for driving said third gear.

17. In a coin selector and slug rejector, a rotatable die, means for rotating said die, means for giving said die a reciprocating motion along its rotation axis, a suction device for exhausting air through the die to cause a coin engaged by the die to adhere thereto, and means including a single cam for controlling said reciprocating motion and the operation of said suction device in timed relation to each other.

18. In a coin selector and slug rejector, a rotatable die, means including a gear for rotating said die to cause the same to fit a deposited coin, a bellows, a spring for expanding said bellows, an air passage whereby the expansion of said bellows exhausts air through said die to cause said coin to adhere thereto after a fit has been established, and a cam rotating with said gear for compressing said bellows and for releasing it in timed relation to the rotation of the die.

19. In a coin selector and slug rejector, a pair of oppositely disposed spaced dies, means for supporting a deposited coin between said dies, said means comprising a normally fixed member and a movable member operated by the weight of the coin, a switch actuated by said movable member, means controlled by said switch for causing said dies to test and select the coin, and manually operated means for operating said normally fixed member to release a deposited coin or slug which fails to cause said movable member to actuate said switch.

20. In a coin selector and slug rejector, a pair of oppositely disposed spaced dies, means for supporting a coin between said dies, a coin chute for directing a coin to said supporting means, means for arresting a sticky coin in said coin chute, means for releasing said coin, means for withdrawing said supporting means and spreading said dies to permit the released coin to fall through the space between the dies without contacting the dies, and a common operating member for actuating said last means and said coin releasing means.

21. In a coin selector and slug rejector, a die having an impression of a coin on its face, said die having one or more holes extending from the face of the die to the back thereof, a hollow shaft, resilient means including a flexible disc for connecting said die to the end of said shaft, said means forming a closed air passage connecting the hollow shaft with the hole or holes in said die, and means for applying suction to said shaft to draw air through said die, whereby a coin engaged by the die may be caused to adhere thereto.

22. In a coin selector and slug rejector, a die having an impression of a coin on its face, said die having one or more holes extending through it from face to back, a hollow shaft, resilient means removably connecting said die to the end of said shaft, said means forming an air passage connecting the hollow shaft with the hole or holes in said die, and means for applying suction to said shaft to draw air through said die, whereby a coin engaged by the die may be caused to adhere thereto.

23. In a coin selector and slug rejector, a die having an impression of a coin on its face, means for moving said die to engage a deposited coin,

15

means for producing relative rotation between the die and coin, and resilient supporting means for said die adapted to permit tilting of the die about any axis in a plane parallel to the face of the die.

24. In a coin selector and slug rejector, two cylindrical members for engaging the opposite sides of a deposited coin, resilient means for operating said members to hold the coin, two dies located inside said members, respectively, resilient means for pressing the dies against the coin on opposite sides thereof, and means for producing relative rotation between the said dies and said members to enable the coin to enter one of the dies.

25. In a coin selector and slug rejector, two dies having a face configuration adapted to fit one side of a coin to be selected, means effective when said coin is deposited for arresting it in a position between said dies with its center in alignment with the centers of said dies, means for bringing said dies in contact with the opposite sides of said coin,

16

respectively, means for rotating said dies, and means for preventing lateral displacement of said coin in any direction during rotation of said dies, whereby the alignment of the coin with the dies is maintained.

26. A coin selector and slug rejector as claimed in claim 25, wherein the means for preventing lateral displacement of the coin includes means for laterally shifting the coin slightly in case the initial alignment thereof with the dies is not exactly correct.

HAROLD A. SMITH.
